UNITED STATES PATENT OFFICE.

GEORGE A. BURNHAM, OF SAUGUS, MASSACHUSETTS, ASSIGNOR TO SHARS B. CONDIE, JR., OF BOSTON, MASSACHUSETTS.

ELECTRIC SWITCH OR CIRCUIT-BREAKER.

1,337,995.

Specification of Letters Patent. Patented Apr. 27, 1920.

Application filed April 17, 1916. Serial No. 91,576.

To all whom it may concern:

Be it known that I, GEORGE A. BURNHAM, a citizen of the United States, residing at Saugus, in the county of Essex and State of Massachusetts, have invented an Improvement in Electric Switches or Circuit-Breakers, of which the following is a specification.

Oil switches and circuit-breakers are usually constructed in such manner that the 10 bridging-member will open and close the electric circuit which the switch controls in a bath of oil contained in a suitable receptacle which, for reasons of strength, is usually of steel. In switches of relatively small 15 carrying capacity, say 1500 to 2000 amperes, no great difficulty is experienced in dissipating the heat which may be generated in the current carrying members and the heat due to hysteresis and eddy currents in 20 the conductors, the oil receptacle and various parts of the structure. At higher current values, however, great difficulty is experienced in maintaining at a moderate temperature the current conducting components 25 of the switch and the associated switch parts.

Because of the high value of alternating current which the switch is adapted to control, and the resultant comparatively great value of alternating flux surrounding the 30 switch leads and conducting terminals, there is a very high eddy current and hysteresis loss in the iron tank and the temperature of the tank may rise to a very high value. It is possible to lessen such losses in the tank 35 by forming it from a non-magnetic material such, for instance, as brass. With such a tank, however, the initial cost is excessive; and, moreover, due to the physical properties of the non-magnetic material employed, 40 it cannot successfully withstand the high pressure that may occur in the tank upon the opening of the switch and therefore it is exceedingly desirable to employ an oil receptacle or tank constructed of iron or steel.

It is possible to reduce the iron losses in 45 the tank by making the tank of comparatively great dimensions, whereby the walls of the tank are a comparatively great distance away from the conducting leads and 50 other conducting portions of the switch which serve to conduct alternating current. Such a construction of tank, however, is not only exceedingly expensive, but occupies such a volume of space that it cannot be

economically employed in any power station or on any switch board.

I have discovered that there is a relationship between the temperature of the oil bath of a circuit breaker and the current which can with safety be ruptured by the circuit breaker; that by restraining rise of temperature of the oil beyond an empirically determined value, the circuit breaker can safely rupture (and therefore carry while closed) much larger currents than can with safety be ruptured if the temperature of the oil is allowed to increase as it will, if no temperature-restraining or depressing means are employed.

Since it is not practical to reduce the 70 hysteresis and eddy current losses in the tank structure by laminating the walls thereof, as is common practice in electrical design, some means must of necessity be provided for dissipating the heat generated by 75 such losses to thereby maintain to some moderate value the temperature of the walls of the tank, which would otherwise rise to an excessive value.

Consequently an instrumentality for carrying out my invention is in the provision of means for dissipating the heat generated in the walls of the oil receptacle or tank of an oil switch and so maintaining the walls and contained oil at a moderate temperature.

In accomplishing this object of my invention, I may employ an auxiliary cooling or radiating surface attached to the walls of the receptacle or tank in the form of fins, or integrally formed therewith, whereby the increased total radiating surface is sufficient to dissipate the heat generated and so maintain the tank or receptacle at a moderate temperature.

I may also provide the tank with a jacket 95 and circulate a cooling medium such as air, oil, or water, for instance, therethrough, to abstract the heat as rapidly as generated. The choice of the particular means employed to keep cool the walls of the tank and consequently the oil in the tank will depend 100 upon the particular conditions under which the switch is required to operate.

In case air, or water, or other fluid is employed, I prefer to cause it to pass through the receptacle only when predetermined conditions of the circuit exist, such as an overload or rise in the current value, in order

that the cooling-means may be effective only at such time, hence I also provide controlling-means for the cooling-means responsive to such conditions.

5 Figure 1 is a side elevation of an oil switch or circuit-breaker having cooling-means embodying this invention.

Fig. 2 is a vertical section of an oil-containing receptacle and pipes connected therewith to form a portion of a conduit for the supply of a cooling-medium.

10 Fig. 3 is a view of an oil switch and means for supplying a cooling medium, and means for governing the delivery of said cooling-15 medium which is controlled by an overload or other abnormal condition of the circuit.

15 Fig. 4 is a view of a modification of my invention.

20 Referring to the drawing 10 represents a receptacle formed of a magnetic material such as iron or steel and containing oil, in which are submerged the current-carrying components of any usual or suitable form of oil switch. Three receptacles are shown in 25 Figs. 1 and 3, and each has a double wall, see Fig. 2, thereby to form a space 15 between the walls which is preferably, although not necessarily, confined. This space is adapted to form a part of a conduit 30 through or along which there is caused to pass a cooling medium, such as air or water.

35 One manner of carrying out my invention comprises pipes 20 and 21 connected to the receptacle in open communication with the space 15, and air or water from any suitable source is conducted through said pipe 20 to the receptacles and caused to pass from the receptacles through the pipe 21. The air or water may be at or about room temperature or lower, and as it enters the space 15, it cools the walls of the tank or receptacle or prevents the temperature thereof from unduly rising and by thus cooling or maintaining at a low temperature the wall of the 45 receptacle the temperature of the oil and the current-carrying components is also prevented from unduly rising.

50 While it will be advisable under some conditions to maintain the flow of air or water continuously through said conduit, yet it may suffice to produce said flow when predetermined conditions exist in the circuit, such for instance as an overload, hence 55 a valve 25 may be connected in the pipe 20, by which to control the flow of air or water, and said valve may be controlled by an electro-magnet 26, connected in a circuit 27, having a circuit-controller 28, 29, responsive to the energization of a coil 30, which is 60 adjusted and connected in the circuit so as to respond to the overload. With this structure the valve is opened only upon the occurrence of an overload and is closed upon the cessation thereof. Good results, however, 65 are produced by the employment of

other means for cooling the heat dissipating medium, such for instance, as providing the wall of the receptacle with laterally extended projections 40, see Fig. 4, arranged to largely increase the area of the exposed 70 surfaces, whereby the walls of the receptacle are maintained at a low temperature or prevented from becoming unduly heated. The range of the responsive cooling action may be less in the latter instance 75 than in the former, but in many instances such a design of cooling means gives satisfactory results.

By the provision of cooling means to dissipate the heat generated in the walls of the 80 receptacle, the size of the switch unit may be maintained within moderate dimensions and the insulating oil therein maintained at its state of maximum effectiveness.

I claim:—

85 1. The combination, with the characteristic mechanical and electrical factors of an oil circuit breaker, of means to keep down the temperature of the oil.

2. The combination, with the characteristic mechanical and electrical factors of an oil circuit breaker, of means to keep down the temperature of the oil, adjacent to the tank walls.

3. In an electric switch adapted for the control of alternating currents, of an inclosing casing therefor, formed of magnetic material having a tendency to heat due to hysteresis and eddy currents induced in the walls thereof by the alternating flux of the 100 conducting components of the switch, and means to cool the casing.

4. In an electric switch adapted for the control of alternating currents, a casing inclosing current conducting components 105 thereof, said casing being formed of magnetic material and heating due to the alternating flux surrounding the current conducting components and means to abstract heat from said casing.

110 5. In an electric switch adapted for the control of alternating currents, of a metallic casing inclosing current conducting components thereof and heating due to the alternating flux surrounding the current 115 conducting components, and means to abstract the heat generated in said casing.

6. An electric switch adapted for the control of an alternating current circuit, including an inclosing casing formed of magnetic material adapted to be heated by hysteresis and eddy currents induced therein by the alternating flux surrounding the current conducting components of the switch, the temperature rise, due to such 125 heating, limiting the capacity of the switch, and means to increase the capacity of the switch which comprises cooling means associated with the casing.

7. An electric switch adapted for the con- 130

trol of an alternating current circuit, including an inclosing casing formed of magnetic material adapted to be heated by hysteresis and eddy currents induced there-
5 in by the alternating flux surrounding the current conducting components of the switch, the temperature rise, due to such heating, limiting the capacity of the switch, and means to increase the capacity of the
10 switch which comprises artificial cooling means associated with the switch arranged to abstract heat from the casing.

8. An electric switch adapted for the control of an alternating current circuit, including an inclosing casing therefor formed of a material adapted to be heated by the alternating flux surrounding the current conducting components of the switch, the temperature rise, due to such heating, lim-
15 iting the capacity of the switch, and means to increase the capacity of the switch which comprises artificial cooling means associated with the switch arranged to abstract heat from said casing and maintain the tempera-
20 ture thereof at a low value.

9. An electric switch having a casing containing oil in which some of the components are immersed, and characterized by said casing adapted to be heated by the current
30 carried by the switch and determining the current carrying capacity of the switch by the temperature rise, and means for increasing the current carrying capacity of the switch which comprises cooling means asso-
35 ciated with said casing adapted to abstract heat therefrom.

10. An electric switch having a casing containing oil in which some of the components are immersed, and characterized by
40 said casing adapted to be heated by the current carried by the switch and determining the current carrying capacity of the switch by the temperature rise, and means increasing the current carrying capacity of the
45 switch which comprises cooling means associated with said casing adapted to abstract heat therefrom, and from the oil and other switch components.

11. An electric switch having a casing
50 containing oil in which some of the components are immersed and characterized by said casing adapted to be heated by the current carried by the switch and determining the current carrying capacity of the switch by the temperature rise, and means for in-
55 creasing the current carrying capacity of the switch which comprises cooling means asso-
60 ciated with said casing and other switch components and adapted to abstract heat from all of them.

12. Apparatus including artificial means for maintaining a reduced temperature and an electric switch having its circuit controlling component arranged in the field of said
65 means to be influenced thereby.

13. An electric switch adapted for the control of an alternating current circuit having components thereof adapted to be heated by the current carried by the switch, and the temperature rise due to such heating
70 limiting the capacity of the switch and means for increasing the current carrying capacity of the switch comprising artificial cooling means associated with said components to abstract heat therefrom and main-
75 tain the temperature of said components at a low value.

14. An electric switch comprising com-
ponents adapted to be heated by the current carried by the switch, the temperature rise
80 thereof limiting the capacity of the switch, and cooling means for said heated compo-
nents adapted to control the temperature rise thereof, whereby it may be maintained at a low value and the current carrying
85 capacity of the switch increased.

15. An electric switch having a casing containing oil in which some of the components are immersed, and characterized by such oil serving to abstract heat from the
90 components, and means for increasing the current carrying capacity of the switch comprising cooling means associated with the switch, adapted to abstract heat from the oil and thereby maintain its temperature
95 rise of low value.

16. An electric switch comprising com-
ponents adapted to be heated by the current carried by the switch, the temperature rise
thereof limiting the capacity of the switch,
100 an insulating, heat-absorbent fluid in which certain of said components are immersed by which the circuit-interrupting arc is dissipated and the heat of said components ab-
sorbed, and artificial cooling means for said
105 insulating fluid to maintain the temperature of said fluid at a low value and thereby in-
crease the current-carrying capacity of the switch.

17. An electric switch comprising com-
ponents adapted to be heated by the current carried by the switch, the temperature rise
110 thereof limiting the capacity of the switch,
an insulating, heat-absorbent fluid in which certain of said components are immersed by
115 which the circuit-interrupting arc is dissipated and the heat of said components ab-
sorbed, said fluid being thereby heated, and means to present cool arc-dissipating, heat-
120 absorbent fluid to said components which comprises cooling means associated with
said fluid.

In testimony whereof, I have signed my name to this specification, in the presence of two subscribing witnesses.
